(57) **CLAIM**

The ornamental design for needle counter, as shown and described.

DESCRIPTION

FIG. 1 is a front view of a needle counter, showing my new design;

FIG. 2 is a right side view with the left side being a mirror image thereof;

FIG. 3 is a top view with the bottom being a mirror view thereof;

FIG. 4 is a back plan view thereof; and,

FIG. 5 is a cross sectional view taken along line 5—5 as shown in FIG. 1.

My new design shows precut sponge blocks that are substantially cylindrical in shape and arranged in rows and columns on a thin releasing paper. Only cylindrical shaped sponge blocks are present on the releasing paper
